DESIGN FOR A COMBINED SCORE TABLE AND SCORE PROJECTOR OR SIMILAR ARTICLE

Ellery J. Cloutier, Muskegon, Mich., assignor
to Brunswick-Balke-Collender Company, Chi-
cago, Ill., a corporation of Delaware

Application February 6, 1942, Serial No. 105,360

Term of patent 14 years

To all whom it may concern:

Be it known that I, Ellery J. Cloutier, a citizen of the United States, residing in the city of Muskegon, county of Muskegon, State of Michigan, have invented a new, original, and ornamental Design for a Combined Score Table and Score Projector or Similar Article, of which the following is a specification, reference being had to the accompanying drawing, forming a part thereof.

Figure 1 is a perspective view on a reduced scale of a combined score table and score projector or similar article, showing my new design;

Figure 2 is a side elevational view thereof;
Figure 3 is a rear elevational view thereof;

Figure 4 is a top plan view thereof, the up-
standing portion illustrated in dotted lines in
Figs. 1, 2 and 3 being omitted.

The dominant features of the design are shown in full lines.

I claim:

The ornamental design for a combined score table and score projector or similar article, as shown and described.

ELLERY J. CLOUTIER.
